26 Claims.

(Cl. 12—7)

The present invention relates to machines for shaping uppers over lasts and is herein illustrated as embodied in a machine of the same general type as that disclosed in United States Letters Patent No. 1,018,477, granted February 27, 1912, on an application of Matthias Brock. The machine herein illustrated is particularly adapted to operate on uppers provided with insole-attaching margins and provided also with outturned outsole-attaching margins, for example, a pre-welted upper provided with a welt having both an outsole-attaching flange and an insole-attaching flange, but it is to be understood that the invention is not limited in its scope to machines for operating on such shoes, certain features of the invention being applicable to machines for lasting other types of shoes, for example, stitchdown shoes.

It is an object of the present invention to provide an improved machine of the type disclosed in the patent above referred to which may be employed to grip the outwardly extending flange of a pre-welted or stitchdown upper, to tension such an upper heightwise of its last and to last a margin of the upper to an insole on a last bottom. More particularly, it is an object of the present invention to provide an improved machine for shaping over lasts uppers provided with insole-attaching margins and provided also with outturned outsole-attaching margins.

With the above and other objects in view a feature of the invention consists in the provision in a machine for shaping over lasts uppers provided with insole-attaching margins or flanges and provided also with outturned outsole-attaching margins or flanges, a clamping member or plate constructed and arranged to engage an end portion of an upper on its last and to support the upper by engagement with its outsole-attaching flange, and an end-lasting member or wiper for laying the insole-attaching flange over upon the margin of the insole. In accordance with a further feature of the invention the clamping member and the lasting member are relatively movable heightwise of the last to engage the outsole-attaching margin therebetween and to hold it during relative movement of said members and the last to tension the upper heightwise thereof. Said members are mounted in a carrier herein illustrated as the vertically movable toe head common to machines of the type above referred to on which said members and said plates are mounted for movement heightwise of the last, and a common actuator for operating said clamping members and wiper members to force

the upper against the last and for thereafter operating the lasting wipers to lay the lasting margin of the upper, for example the insole-attaching margin above referred to, over upon an insole on the last bottom. The illustrated end-lasting wiper plates are removably attached to arms mounted on carriers, or plates, for movement heightwise of the last relatively to the clamping members, the common actuator above referred to having connections to the carriers for operating the wiper plates. The illustrated carriers are substantially similar in their construction and operation to wiper carrier plates commonly employed in bed lasting machines of the type above referred to. The wiper plates above referred to are yieldingly urged away from the clamping plates and a member is provided for moving the wiper plates toward the clamping plates to grip the margin of the upper therebetween. In accordance with a further feature of the invention, the illustrated machine is provided with an end-embracing band for pressing an upper against a last in the machine and end-embracing lasting wipers spaced above said band and constructed and arranged to engage the outsole-attaching face of the outturned outsole-attaching margin of an upper of the type above referred to. The space between the band and the wipers is substantially equal to the thickness of the outturned margin of the upper. For gripping each side portion of the upper by its outsole-attaching margin and tensioning the side portions of the upper heightwise thereof and shaping the upper to the last the illustrated machine is provided with gripper plates relatively movable heightwise of a last in the machine to grip the margin of the upper therebetween, said plates being adjustable lengthwise of the shoe. For working the side portions of the upper in against the last the illustrated machine is provided with a common actuator for moving the side grippers toward the last. The gripper plate which engages the sole-attaching face of the outturned flange of the upper is constructed and arranged to wipe the insole-attaching flange over upon the margin of an insole on the last bottom after the plate which engages the opposite face of the outturned flange has been arrested by the engagement of the upper with the last.

These and other features of the invention will now be described with reference to the accompanying drawings and pointed out in the appended claims.

In the drawings,

Fig. 1 is a front elevation of a bed lasting

machine embodying the features of the present invention;

Fig. 2 is a plan view of the machine, the opposite end portions being broken away;

5 Fig. 3 is a sectional view taken substantially on the line III—III of Fig. 2;

Fig. 4 is a sectional elevation taken substantially on the longitudinal median line of the forepart of a shoe in the machine and illustrating 10 certain operating parts in the toe head in relation to the shoe;

Fig. 5 is a sectional elevation similar to Fig. 4 showing the operating parts in different positions from those illustrated in Fig. 4;

15 Fig. 6 is a sectional elevation similar to Figs. 4 and 5 showing the operating parts in their final positions at the end of the lasting operation;

Fig. 7 is a sectional elevation looking toward 20 the toe end of a shoe in the machine and illustrating particularly the devices for lasting the side portions of the shoe;

Fig. 8 is a sectional elevation similar to Fig. 7 illustrating the lasting devices at one side of the shoe in different positions from those illustrated 25 in Fig. 7;

Fig. 9 is a sectional elevation similar to Fig. 8 illustrating the lasting devices in their positions at the end of the lasting operation;

30 Fig. 10 is a sectional view of the work-engaging members illustrated in Figs. 8 and 9 taken substantially on the line X—X of Fig. 8;

Fig. 11 is a perspective view of parts of the side-lasting assembly illustrated in Fig. 7;

35 Fig. 12 is a perspective view of lasting devices at one side of the toe head vertically separated from each other to disclose certain details of construction; and

Fig. 13 is a detail plan view of one of the forepart-lasting members.

40 The machine illustrated in the drawings is similar in its general organization to the machine disclosed in the patent to Brock above referred to. Referring to Fig. 1, the illustrated machine is provided with a toe rest 20 and a rear part supporting member 22. The lasting devices 45 which operate on the end portions of a shoe in the machine are mounted, respectively, in a toe head 24 and a heel head 26 which are provided with the usual adjusting means for positioning the lasting devices relatively to the shoe, including 50 a hand screw 27 for swiveling the toe-lasting devices about an axis extending generally lengthwise of a shoe in the machine, a hand screw 29 for rocking said devices about an axis 55 extending transversely of the shoe, and another hand screw 31 for moving the toe head toward and from the heel head.

60 The heel head 26 carries a rear-part-embracing band 28 the upper edge face of which, as illustrated in Fig. 3, is positioned below the under surfaces of the heel wipers 30 substantially to the extent of the thickness of a welt attached to an upper 34 in the machine. The illustrated welt comprises parallel flanges 31 between which the margin of the upper is secured and flanges 32 and 36 which are secured to the outsole and the insole, respectively. It will be seen that the under surfaces of the heel wipers 30 engage the sole-attaching face of the flange 32 while the 65 upper edge face of the heel band 28 engages that face of the flange 32 which is exposed in the finished shoe. The shoe is forced rearwardly thereof into the heel band 28 by power-operated means operating on the rear-part-supporting member 22. As illustrated in Fig. 2 the heel- 70

75 seat wipers 30 operate to lay the insole-attaching flange 36 of the welt over upon the margin of an insole 38 on the bottom of a last in the supported upper. Preferably the margin of the insole 38 and also the insole-attaching face of the flange 36 are coated with adhesive in order to secure the parts in lasted position.

For tensioning the forepart of the upper heightwise of the last the toe head 24 is provided with two pairs of forepart-embracing plates 40 and 42 (Fig. 4) which grip the outsole-attaching flange 32 between them while the toe head moves upwardly, carrying the welted margin of the upper with it. Such upward movement of the toe head is effected by the operation of a 15 treadle 44 (Fig. 1) which is connected to the toe head by a link 46 and a slide 47, said treadle and its connections being substantially the same as corresponding parts disclosed in U. S. Letters Patent No. 1,373,482, granted April 5, 1921 on 20 an application of Matthias Brock. During the upward movement of the toe head a last 48 positioned in the upper is held from heightwise movement by a holdown plate 50 (Fig. 4) which is operated by a treadle 52 (Fig. 1) to press the 25 forepart of the last downwardly against the toe rest 20 and is held in work-engaging position, as illustrated in Fig. 4, by the engagement of a pawl (not shown) with a ratchet slide 54 connected to the treadle. The construction and arrangement of the holdown assembly is substantially 30 the same as in the patent to Brock No. 1,373,482 above referred to. After the welted margin of the upper has been drawn upwardly into its position illustrated in Fig. 5 the forepart-embracing plates 40 and 42 are operated in unison by the usual toe-wiper lever 56 (Fig. 1) to press the 35 welted margin of the upper firmly against the last and thereafter the lever 56 is further advanced to cause the forepart-embracing plates, or clamping plates 40 are held in gripping engagement with the upper. Referring now to Fig. 4, illustrating 40 one of the plates 40, the illustrated plate is mounted on the rabbeted margin 60 of a carrier plate 62 and removably secured thereto by 45 a headed screw 64. The carrier plate 62 is slidably mounted on a base plate 66 provided in the toe head 24 and its operating movements toward and from the shoe are controlled and directed by rolls 68 and 70 (Fig. 12) which are 50 pivoted on studs projecting upwardly from the base plate 66 and positioned in arcuate grooves 72 and 74 respectively provided in the plate 62. For operating the forepart-embracing plates 40 the lever 56 above referred to is connected to 55 a plunger 76 constructed and arranged for movement lengthwise of the shoe in the machine and provided at its end nearest the supported shoe with a crosshead 78 which, as illustrated in Fig. 12, carries at one end thereof a downwardly extending stud 80 provided with a diametrical hole through which extends one end of a stem 82, the opposite end of the stem being secured to a block 84 which has a cylindrical upward extension 86 mounted for swiveling movement in a hole in 60 the carrier plate 62. In order to permit continued movement of the forepart-embracing plates 42 after the plates 40 have been arrested by engagement with the upper 34, yielding connections are provided between the plunger 76 65 and the carrier plate 62. 70

75

80

85

90

95

and the carrier plates 62. One of said connections is illustrated in Fig. 12 and comprises a spring 88 surrounding the stem 82 and confined between the block 84 and a square plate 90 loosely mounted on the stem 82 and arranged to engage the stud 80 extending downwardly from the crosshead 78. The expansion of the spring is limited by the engagement of a washer 92 on the end of the stem 82 with the stud 80, the washer being backed up by a cotter pin 94. The forepart-embracing plate 42 illustrated in Fig. 4 is removably secured to a swinging arm 96 (Fig. 13) which, as illustrated in Fig. 12, is pivoted at the end of its arm 97 between upstanding ears 98 on a carrier plate 100. The plate 42 is secured in a rabbeted margin in the under surface of the inwardly extending arm 99 (Fig. 13) of the member 96 by a clamping screw 101 the head of which engages a rabbeted top margin of the arm 99. As illustrated in Fig. 4, the carrier plate 100 is supported upon the carrier plate 62 which carries the forepart-embracing plate 40 and its movements are controlled and directed by rolls 102 and 104 which are mounted coaxially with the rolls 68 and 70 and are positioned in arcuate grooves 106 and 108 respectively provided in the carrier plate 100. The swinging arm 96 is yieldingly held in its elevated position, as illustrated in Fig. 4, by a spring 110 one end of which surrounds a stud 112 extending downwardly from the arm 96 and the opposite end of which engages the upper surface of the carrier plate 100. The connection from the plunger 76 to the carrier plate 100 illustrated in Fig. 12 comprises a link 114 which is swiveled to one end of the crosshead 78 and provided at its free end with an upwardly extending cylindrical head 116 which is positioned in a socket extending upwardly into the carrier plate 100. In order that the forepart-embracing plate 42 may be positioned accurately with relation to the work the swinging arm 96 illustrated in Fig. 12 is provided with a tongue and groove connection to the carrier plate 100 adjacent to the free end of said arm, said connection comprising a tongue 118 which extends upwardly from the carrier plate 100 and is positioned within a groove 120 provided in an offset portion 122 of the arm 96. It will be seen that the tongue and groove connection above described permits swinging movement of the arm 96 to bring the forepart-embracing plates 42 into engagement with the outsole-attaching face of the welt 32 as illustrated in Fig. 5. It will be understood that the forepart-embracing plates 40 and 42 which are not illustrated in Fig. 12 correspond in construction and arrangement to the plates 40 and 42 illustrated therein, as do also the operating parts therefor. For swinging the plates 42 from their position in Fig. 4 to their welt-engaging position illustrated in Fig. 5 the illustrated machine is provided with a lever or rocker member 124 which, as illustrated in Fig. 2, is generally V-shaped and provided with outwardly extending hubs 126 whereby it is pivotally mounted between brackets 128 extending upwardly from the top plate of the toe head. At the opposite extremities of its V portion the rocker member 124 is provided with a pair of downwardly extending ears 130, and between each pair of ears there is pivotally mounted a roll 132 which is arranged to engage one of the swinging arms 96. When the rocker member 124 is in its position illustrated in Fig. 4 the swinging arms 96 are held at the limit of their upward movement by the springs 110, such limit

being determined by the engagement of the arms with the rocker member. When it is desired to bring the plates 42 into engagement with the outsole-attaching face of the welt 32 the rocker member is swung from its position in Fig. 4 to its position in Fig. 5 and during such movement of the rocker member, the rolls 132 move downwardly simultaneously, traveling about the axis of the rocker member until the movement of the rocker member is arrested by the engagement of a downward extension 134 (Fig. 1) thereof with an adjustable stop screw 136 mounted in an extension of one of the brackets 128. Preferably the stop screw 136 is so adjusted that the rolls 132 move sufficiently beyond their dead center positions to insure that they will be held in the positions illustrated in Fig. 5 by the action of the springs 110 which tend to return the swinging arms 96 to their elevated positions. To facilitate the operation of the rocker member 124 it is provided with an upwardly extending handle 138 (Figs. 1 and 2). It will be seen that the rolls 132 hold the plates 42 in their work-engaging positions as said plates are advanced from their positions in Fig. 5 to their positions illustrated in Fig. 6 in order to wipe the insole-attaching flange 36 over upon the margin of the insole 38. For shaping the opposite side portions of the upper 34 to the last 48 the illustrated machine is provided with plates 140 constructed and arranged to engage opposite side portions of the outsole-attaching flange 32, said plates engaging that face of the flange which is exposed in the finished shoe. The work-engaging edges of the plates 140 as seen in plan (Fig. 2) and also as seen in elevation (Fig. 10) conform to the edge face of the insole 38 when they are brought into work-engaging position, as illustrated in Fig. 8. The plates 140 are removably mounted on vertical arms 142 which, as hereinafter described, are supported on arms 144 mounted on the lower portion of the toe head and arranged to extend toward the heel head, the portions of said arms 144 nearest the heel head being offset downwardly and inwardly from their forward end portions (Fig. 11). Thus it will be seen that the plates 140 move upwardly with the toe head 24 and operate to tension the side portions of the upper heightwise of the last. During such upward movement of the toe head the side portions of the outsole-attaching flange 32 are clamped against the plates 140 by plates 146 which are constructed and arranged to swing downwardly into engagement with the outsole-attaching face of the flange. As illustrated in Fig. 2, the inner edges of the plates 146 have substantially the same shape as the edge of that portion of the shoe bottom on which they operate. The welt-engaging plates 146 are removably secured to rocker arms 148 which are pivotally mounted between upward extensions of slides or channel plates 150, the construction and arrangement of which are hereinafter described. Referring now to Fig. 10 illustrating the welt-engaging plates 140 and 146 at the front of the machine, the plate 140 is provided with a downward extension 152 the bottom edge of which is an arc the center of curvature of which lies in the plane of the welt-engaging surface of the plate 140. The extension 152 of the plate 140 is positioned in a rabbeted portion of the arm 142 the bottom wall of which has the same curvature as the bottom edge face of the extension and provides a guiding surface upon which the plate 140 is swiveled to adjust it to the profile of a given run of shoes to be operated upon. The plate 140 is secured in adjusted position by a

clamping screw 154 which extends through an arcuate slot 156 in the downward extension 152 of the plate and into a tapped hole in the arm 142. Similarly, the welt-engaging plate 146 is provided 5 with an upward extension 158 which is mounted on a head 160 provided at the inner end of the rocker arm 148. The upper edge face of the extension 158 is an arc the center of curvature of which lies in the plane of the welt-engaging face 10 of the plate 146 and engages a corresponding arcuate guiding surface or shoulder provided by an arcuate flange 162 at the upper extremity of the head 160. The plate 146 is adjusted to position it in parallel relation to the plate 140 and is 15 secured in that position by a clamping screw 164 which extends through an arcuate slot 166 in the upward extension 158 of the plate 146 and into a tapped hole in the head 160. The slide 150 illustrated in Fig. 8 comprises a channel plate mounted 20 on a swinging arm 168 which has formed at its lower end a yoke 170 which straddles a boss 172 (Fig. 7) projecting upwardly from a plate 174 which carries the heel head. The plate 174 is substantially the same in its construction and 25 operation as a corresponding plate in the machine illustrated in the patent to Brock No. 1,018,477 above referred to. As illustrated in Fig. 1, the plate 174 is pivotally mounted on a pin 175 projecting upwardly from the frame upon which pin 30 it swings in a horizontal plane to adjust the heel wipers 32 to the longitudinal median line of the rear portion of a shoe in the machine. The downwardly extending arms of the yoke 170 are pivotally mounted on a crosspin 176 carried by the 35 boss 172 and this boss is substantially narrower than the distance between the arms, thus permitting a limited bodily movement of the entire side-lasting assembly lengthwise of the shoe in the machine to adjust the welt-engaging plates to the 40 shoe (Fig. 1). As illustrated in Fig. 1 the slide 150 is held in sliding engagement with the arm 168 by gib 178 secured to bosses projecting outwardly from the flanges of the slide 150. Referring again to Fig. 8, the lower portion of the slide 150 is pro- 45 vided with inwardly extending arms 180 between the ends of which the lower portion of the arm 142 is pivotally mounted. There is also mounted between the arms 180 a roll 182 which engages a plate 184 mounted on one of the arms 144 of the 50 toe head and thus providing a support for the slide 150 and the work-engaging plates 140 and 146 carried thereby. In order to provide convenient means for adjusting the height of the work-engaging plates 140 and 146 when changing from right 55 to left shoes and vice versa the plate 184, as illustrated in Fig. 11, is provided with supporting surfaces 186 and 188 arranged at elevations which differ substantially to the same extent as the difference in elevation of the opposite sides of the 60 shank portion of the shoe as illustrated in Fig. 7. The plate 184 is swiveled on a pin 185 projecting upwardly from the arm 144 and provided with a headed pin 186 which extends through either of two holes 188 provided in opposite ends of the 65 plate 184 and into a socket in the arm 144, thereby locating the plate and locking it in a position such that the shoulder 194 between the surfaces 186 and 188 is parallel to the path of movement of the roll 182. Preferably, the roll 182 is positioned on the 70 plate 184 between the shoulder 194 and that end face of the plate which faces the heel head. In order to maintain this position of the roll it is, of course, necessary that the arms 144 be adjustable in order to relocate the plates 184 after adjusting 75 the toe head lengthwise of the shoe. To afford

such adjustment the illustrated arms 144 are each secured to the base of the toe head by two clamping screws 220 which pass through longitudinal slots 222 provided in the arms 144 respectively, these slots being somewhat longer than the distance between the screws in order to permit the required adjustment. It will be understood that the plates 184 will always be arranged in opposite positions, that is, when one of the plates presents its surface 186 to the supporting roll 182 the other 10 plate will be arranged to present its surface 188 to the corresponding roll at the opposite side of the machine (see Fig. 11). For swinging the rocker arm 148, illustrated in Fig. 8, to bring the plate 146 into and out of its welt-engaging position, the 15 slide 150 has pivoted thereto at 195 a yoke 196 which, as illustrated in Fig. 1, straddles the slide 150 and is arranged with its crossbar above the top of the slide when the plate 146 is in its welt-engaging position. The parallel arms of the yoke 20 196 are provided, respectively, with outwardly projecting lugs which carry bosses 198 (Fig. 1) extending lengthwise of the supported shoe toward each other and into position to engage the flanges of the slide 150 during movement of the yoke 25 toward the shoe in the machine, these bosses having pivoted to their inner ends links 200 which extend upwardly from the bosses and are pivoted at their upper ends to the outer end of the rocker arm 148. The links 200 form one element of a 30 toggle for swinging the rocker arm 148 to move the plate 146 toward and from welt-engaging position, the other element of the toggle being the yoke 196. The straightened position of the toggle as 35 illustrated in Fig. 8 is determined by the engagement of the bosses 198 with the slide 150, in which position of the toggle the bosses 198 have passed slightly beyond a dead center position. For advancing the work-engaging plates 146 from the 40 positions illustrated in Fig. 8 to the positions illustrated in Fig. 9 the illustrated machine is provided with a right and left threaded screw 202 provided with a hand wheel 203 (Fig. 7) the opposite ends of which are provided with nuts 204 which are positioned in holes in the arms 168 and are provided with bosses 206 extending diametrically from opposite sides of the nuts, the bosses being triangular in cross section and providing fulcrum edges which engage the arms 168 in V-shaped notches 208 provided in the opposite walls of the 50 holes which receive the nuts 204. The arms 168 are urged outwardly against the nuts 204 by a spring 210 surrounding the hand screw 202, the opposite ends of said spring engaging the inner surfaces of the arms. For positioning the work- 55 engaging plate 140 in opposition to the work-engaging plate 146 as illustrated in Fig. 8 lugs 212 project outwardly from opposite sides of the lower portion of the arm 142 and are provided with holes through which extend bolts 214 the threaded ends 60 of which extend through suitable holes in lugs 216 extending outwardly from the lower portion of the slide 150. Springs 218 surrounding the bolts 214 yieldingly hold the arm 142 in the position illustrated in Fig. 8 while permitting the plate 146 to 65 be advanced from its position in Fig. 8 to its position in Fig. 9 by turning movement of the hand screw 202. It will be understood that the hand screw operates simultaneously and uniformly on the work-engaging plates at opposite sides of the 70 shoe in the machine. It will also be understood that so much of the above description as refers specifically to the construction illustrated in Fig. 8 defines equally well the corresponding mechanism at the opposite side of the machine. 75

In accordance with the preferred operation of the illustrated machine a pre-welted upper which has been assembled on the rear portion of a last is positioned in a machine with the outsole-attaching welt flange 32 at the heel portion of the upper positioned on the upper edge face of the heel band 28 while said outsole-attaching welt flange at the toe portion of the upper is supported upon the plates 40. After the upper on its last has been positioned in the machine the holdown 50 is brought into operative position as illustrated in Fig. 4. The lever 124 which operates the toe-embracing plates 42 is then swung downwardly to bring the plates 42 into engagement with the outsole-attaching face of the welt. The side-lasting assemblies are then swung from their positions in Fig. 7 into engagement with the work by turning the hand screw 202 and after the plates 140 have entered the welt crease the yokes 196 are swung upwardly to bring the plates 146 into gripping engagement with the outsole-attaching face of the welt. Having thus gripped the outwardly extending flange of the welt at the toe and side portions of the upper the operator rocks the treadle 25 (Fig. 1), thereby lifting the toe head 24 together with the side-lasting assemblies and pulling the forepart and the opposite side portions of the upper heightwise of the last. After the operation of the treadle 24 the toe portion of the upper is in the position illustrated in Fig. 5 and the side portions are in the positions illustrated in Fig. 8. The lever 56 which operates the toe-embracing plates 40 and 42 is now advanced to press the welted margin of the upper firmly against the last 35 and against the edge face of the insole 38 and thereafter is further advanced to cause the plates 42 to wipe the insole-attaching flange 36 over upon the margin of the insole. The heel seat lasting wipers 30 are then advanced to last the rear portion of the insole-attaching flange to the insole and then the hand screw 202 is operated to bring the side portions of the welted margin of the upper firmly against the last and to cause the side wiper plates 146 to last the side portions of the 45 insole-attaching flange to the insole. Preferably, the insole-attaching flange 36 is initially secured in lasted position by adhesive with which it has been treated prior to the lasting operation. Preferably, an adhesive which sets rapidly is employed in order to permit the shoe to be removed from the machine as soon as practicable after the completion of the lasting operation. It is, of course, obvious that fastenings such, for example, as lasting tacks, may be employed to secure the upper in lasted position if desired.

While the invention has been illustrated in its application to the lasting of a pre-welted shoe provided with a welt strip having both an outsole-attaching flange and an insole-attaching flange, it is to be understood that the invention is not thus limited in its scope but is applicable to the lasting of any type of shoe provided with an outturned sole-attaching flange and with an insole-attaching flange. For example, the illustrated machine could be employed to last a stitchdown shoe in the manufacture of which the lining is lasted inwardly over the margin of an insole. In certain of its aspects the invention is applicable to machines for operating on uppers provided with outturned sole-attaching flanges but not provided with insole-attaching flanges as herein illustrated. For example, the illustrated machine is well adapted to last the usual type of pre-welted uppers, that is, uppers in which a 75 welt strip which provides an outsole-attaching

means only is secured to the lasting margin before the upper is lasted.

Having thus described my invention, what I claim as new and desire to secure by Letters Patent of the United States is:

1. In a machine for shaping over lasts uppers provided with insole-attaching margins and provided also with outturned outsole-attaching margins, a clamping plate constructed and arranged to engage an end portion of an upper on its last and to support the upper by engagement with its outsole-attaching margin, and an end lasting wiper for laying the insole-attaching margin of the upper over upon the margin of the insole. 15

2. In a machine for shaping over lasts uppers provided with insole-attaching flanges and provided also with outturned outsole-attaching flanges, means for gripping an upper by its outsole-attaching flange comprising members relatively movable heightwise of a last in the machine to engage the outsole-attaching flange therebetween, and means for operating the member which engages the outsole-attaching face of said flange to lay the insole-attaching flange of the upper over upon the margin of an insole on the last bottom. 20

3. In a machine for shaping over lasts uppers provided with insole-attaching margins and provided also with outturned outsole-attaching margins, clamping plates constructed and arranged to engage respectively opposite faces of the outsole-attaching margin of an upper in the machine, one of said plates being movable relatively to the other in the plane of the shoe bottom to 30 last the insole-attaching margin over upon an insole on a last in the machine. 35

4. In a machine for shaping over lasts pre-welted uppers provided with insole-attaching flanges, a clamping plate constructed and arranged to engage a pre-welted upper within the welt crease, and a wiper plate movable heightwise of the upper to clamp the welt against said clamping plate and movable to wipe the insole-attaching flange over upon the margin of an insole on the bottom of a last in the upper. 45

5. In a machine for shaping over lasts pre-welted uppers provided with insole-attaching flanges, a clamping plate constructed and arranged to engage a pre-welted upper within the welt crease, a wiper plate for clamping a welt against said clamping plate, and means for moving said plates in unison in a plane substantially parallel to the shoe bottom to press the upper against a last in the machine and for moving the wiper plate to lay the insole-attaching flange over upon an insole on the last bottom. 50

6. In a machine for shaping over lasts pre-welted uppers provided with insole-attaching flanges, a clamping plate constructed and arranged to engage a pre-welted upper within the welt crease, a wiper plate, means for moving the wiper plate heightwise of the upper to clamp the welt against said clamping plate and for holding the wiper in clamping engagement with the welt, 60 and an actuator for first moving the plates in unison while their clamping engagement with the welt is maintained and for moving the wiper plate relatively to the clamping plate to lay the insole-attaching flange over upon an insole on a 65 last in the machine after the clamping plate has been arrested by the last.

7. In a lasting machine, end-embracing members for forcing an upper against a last in the machine, end-lasting wiper plates, a vertically 70

movable support for said members and said plates on which said plates are mounted for operative movement heightwise of the last relatively to said members, and a common actuator for operating said members to force the upper against the last and for thereafter operating said wiper plates to lay the lasting margin of the upper over upon an insole on the last bottom.

8. In a lasting machine, end-embracing gripper plates, carriers to which said plates are removably attached, end-lasting wiper plates, arms to which said wiper plates respectively are removably attached, carriers on which said arms are mounted for movement heightwise of the last, a common actuator for all said carriers, a yielding connection from the actuator to the gripper plate carriers, and an unyielding connection from the actuator to the wiper plate carriers.

9. In a lasting machine, end-embracing gripper plates, carriers to which said plates are removably attached, end-lasting wiper plates, arms to which said wiper plates respectively are removably attached, carriers on which said arms are mounted for movement heightwise of the last, a common actuator for all said carriers, a yielding connection from the actuator to the gripper plate carriers, an unyielding connection from the actuator to the wiper plate carriers, a head in which said carriers are mounted, means on the head for directing the movements of the carriers, and means for moving the head heightwise of the last.

10. In a lasting machine, a gripper plate, a wiper plate movable heightwise of a last in the machine relatively to the gripper plate, yielding means for urging the wiper plate away from the gripper plate, a member for moving the wiper plate toward the gripper plate to grip an upper therebetween, and means for moving the wiper plate relatively to the gripper plate in a plane parallel to the last bottom thereby to last a marginal portion of the upper to an insole on the bottom of the last.

11. In a lasting machine, a gripper plate, a carrier therefor, a wiper plate, an arm to which the wiper plate is attached, a carrier on which the arm is mounted for movement heightwise of a last in the machine, yielding means for urging said wiper plate away from the gripper plate, a member for moving said wiper plate toward the gripper plate and for holding the wiper plate in a position adjacent to the gripper plate, and means constructed and arranged to operate on said carriers to advance said plates in unison until the gripper plate is arrested by a last in the machine and thereafter to advance the wiper plate over the margin of the last bottom.

12. In a machine for shaping over last uppers provided with insole-attaching flanges and provided also with outturned outsole-attaching flanges, a member for pressing an upper against a peripheral face of a last in the machine, one marginal face of said member being constructed and arranged to engage that face of the outsole-attaching flange opposite its sole-attaching face, and means for lasting the insole-attaching flange of the upper to the margin of an insole on the last bottom.

13. In a machine for shaping over lasts uppers provided with insole-attaching flanges and provided also with outturned outsole-attaching flanges, an end-embracing band for pressing an upper against the periphery of a last in the machine, the upper edge face of said band being constructed and arranged to support the upper

by engagement with its outsole-attaching flange, and end-embracing wipers for laying the insole-attaching flange of the upper over upon the margin of an insole on the last bottom.

14. In a machine for shaping pre-welted uppers over lasts, an end-embracing band for pressing an upper against a last in the machine, and end-embracing lasting wipers spaced above said band and constructed and arranged to engage the sole-attaching face of the welt. 5

15. In a machine for shaping pre-welted uppers over lasts, an end-embracing band for pressing an upper against a last in the machine, said band being constructed and arranged to engage that portion of the upper contiguous to the welt, 15 and end-embracing lasting wipers spaced above said band substantially to the extent of the thickness of the welt for engagement with the outsole-attaching face of the welt.

16. In a machine for shaping pre-welted uppers over lasts, means for gripping a side portion of an upper by its welt comprising gripper plates relatively movable heightwise of a last in the machine to grip the welt therebetween, said plates being adjustable lengthwise of the last. 20

17. In a machine for shaping over lasts uppers provided with insole-attaching flanges and provided also with outturned outsole-attaching flanges, means for gripping a side portion of the upper by its outsole-attaching flange comprising 30 gripper plates relatively movable heightwise of a last in the machine to engage the outsole-attaching flange therebetween, said plates being adjustable lengthwise of the last, and means for operating the gripper plate which engages the 35 outsole-attaching face of said flange to lay the insole-attaching flange of the upper over upon the margin of an insole on the last bottom.

18. In a machine for shaping pre-welted uppers over lasts, means for gripping opposite side 40 portions of a pre-welted upper by its welt comprising gripper plates relatively movable heightwise of a last in the machine to grip the welt therebetween, and a common actuator for moving each gripper assembly bodily as a unit to last the 45 side portions of the upper.

19. In a machine for shaping over lasts uppers provided with insole-attaching flanges and provided also with outturned outsole-attaching flanges, means for gripping an upper by its outsole-attaching flange comprising plates relatively 50 movable heightwise of a last in the machine, means for closing said plates on the outsole-attaching flange of the upper, and a hand screw for moving said plates in a direction to press the 55 upper against the last and for thereafter advancing the plate which engages the outsole-attaching face of the flange to wipe the insole-attaching flange over upon the margin of an 60 insole on the last bottom.

20. In a machine for shaping over lasts uppers provided with insole-attaching flanges and provided also with outturned outsole-attaching flanges, means for gripping opposite side portions 65 of an upper by its outsole-attaching flange comprising plates relatively movable heightwise of a last in the machine to grip the outsole-attaching flange therebetween, means for independently closing the plates at each side of the last upon 70 the outsole-attaching flange, and a common actuator for all said plates which operates first to press the upper against one side of the last and thereafter to cause the plates which engage the outsole-attaching face of said flange to move 75

- toward each other to wipe the insole-attaching flange over upon an insole on the last bottom.
21. In a machine for shaping over lasts uppers provided with outturned outsole-attaching flanges, plates constructed and arranged to engage, respectively, the sole-attaching face of the outsole-attaching flange at opposite sides of an upper in the machine and the face of said flange opposite its outsole-attaching face thereby to hold said flange during relative movement of said plates and a last in the upper to tension the upper over the last, and means for so positioning said plates heightwise of a shoe in the machine that the plates adjacent to the inside of the shank portion of the shoe are higher than the plates at the opposite side.
22. In a machine for shaping over lasts uppers provided with outsole-attaching flanges, a pair of plates constructed and arranged to engage therebetween a portion of the outsole-attaching flange at one side of an upper and to hold said flange during relative movement of said plates and a last in the upper to tension the upper over the last, and means for supporting said plates at either of two predetermined elevations.
23. In a machine for shaping over lasts uppers provided with outsole-attaching flanges, a pair of plates constructed and arranged to engage therebetween a portion of the outsole-attaching flange at one side of an upper and to hold said flange during relative movement of said plates and a last in the upper to tension the upper over the last, arms on which said plates are respectively mounted, and a support for said arms having a plurality of supporting surfaces arranged at different elevations, said support being movable to present any one of said surfaces to said arms.
24. In a machine for shaping over lasts pre-welted uppers provided with insole-attaching flanges, an end-embracing band for pressing an

upper against a last in the machine, end-embracing lasting wipers spaced above said band and constructed and arranged to engage the sole-attaching face of the welt and to wipe the insole-attaching flange over upon an insole on the last bottom, and means for gripping a side portion of the upper by its welt comprising gripper plates relatively movable heightwise of a last in the machine to grip the welt therebetween and to hold it during relative movement of said plates and a last in the upper to tension the upper over the last.

25. In a machine for shaping over lasts uppers provided with outturned outsole-attaching margins, toe-embracing clamping plates constructed and arranged to grip the sole-attaching margin of the toe portion of an upper therebetween and to hold it during relative movement of said plates and a last in the upper to tension the upper over the last, a heel-embracing band for pressing the upper against the last, and heel-lasting wipers spaced above said band substantially to the extent of the thickness of the outsole-attaching margin.

26. In a machine for shaping over lasts uppers provided with outturned outsole-attaching margins, toe-embracing clamping plates constructed and arranged to grip the outsole-attaching margin of the toe portion of an upper therebetween, a heel-embracing band for pressing the upper against a last in the machine, heel-lasting wipers spaced above said band substantially to the extent of the thickness of the outsole-attaching margin, clamping plates constructed and arranged to engage the outsole-attaching margin at opposite sides of the upper, and means for effecting relative movement of the last and the plates which engage the toe and side portions of the upper thereby to tension the upper over the last.

CHARLES E. HOOD.
